Joseph Kay
By his Attorney,
John E. Earle

United States Patent Office.

JOSEPH KAY, OF NEW HAVEN, CONNECTICUT.

Letters Patent No. 91,137, dated June 8, 1869.

IMPROVED TUYERE.

The Schedule referred to in these Letters Patent and making part of the same.

To all whom it may concern:

Be it known that I, JOSEPH KAY, of New Haven, in the county of New Haven, and State of Connecticut, have invented a new Improvement in Tuyere; and I do hereby declare the following, when taken in connection with the accompanying drawings, and the letters of reference marked thereon, to be a full, clear, and exact description of the same, and which said drawings constitute part of this specification, and represent in—

Figure 1, a top view;

Figure 2, a side view;

Figure 3, a transverse section; and in

Figure 4, a diagram, illustrating the operation.

This invention relates to an improvement in tuyeres for forge-fires, and consists, first, in the arrangement of a swinging grate, combined with a slide, so as to admit wind from beneath the fire; and, secondly, in the arrangement of two slides, the one operating upon the other, so as to open the passage to the tuyere centrally, and to an extent double the movement of either slide.

In order to the clear understanding of my invention, I will fully describe the same, as illustrated in the accompanying drawings.

A is the tuyere-plate, into which a circular grate, B, is pivoted at a, so that the grate may be turned, as occasion may require, to the position in fig. 3, it being held in position by a rod, C, working through the tuyere-plate, as denoted in fig. 1.

Beneath the grate is arranged the chamber D, into which air is admitted directly from the blower.

Between the air-chamber and grate, I arrange two slides, b and c, to each of which a rack, E and F, respectively, is fixed, and between the two racks is ar-

ranged a pinion, G, so that by moving one of the slides, the pinion G is turned, causing the movement of the other slide in the opposite direction.

Through the two slides is formed a circular opening, of the same diameter, or nearly so, as the grate-opening, the openings being represented in fig. 4, the upper plate in red and the under plate in blue, and represented as closed; also so represented in fig. 1.

Now, if one, say the upper plate, be drawn out, as from the position in fig. 2, to that in fig. 3, then the openings through the two plates come directly one over the other, and so as to open to the fullest extent the communication between the air-chamber D and the grate, and in this movement the opening commences at the centre, each slide opening from the centre.

The space opened is double the movement of either slide, and when but a small space is required to be opened, as denoted by the broken black lines, fig. 4, then wind is admitted centrally on to the grate, which, as will be readily seen, must have a better effect upon the fire than if opened upon one side or edge of the grate.

Having fully described my invention,

What I claim as new and useful, and desire to secure by Letters Patent, is—

The arrangement, in the tuyere-plate A, of the swinging plate B, combined with the two plates, b and c, each constructed with corresponding openings, and so as to operate substantially in the manner herein described.

JOSEPH KAY.
